UNITED STATES PATENT OFFICE.

WARD DARLEY, OF DENVER, COLORADO, ASSIGNOR OF ONE-HALF TO
GEORGE C. DEWEY, OF WHEELING, WEST VIRGINIA.

COIN-CONTROLLED MECHANISM.

SPECIFICATION forming part of Letters Patent No. 672,403, dated April 16, 1901.

Application filed August 7, 1900. Serial No. 26,191. (No model.)

To all whom it may concern:

Be it known that I, WARD DARLEY, a citizen of the United States of America, residing at Denver, in the county of Arapahoe and State of Colorado, have invented certain new and useful Improvements in Coin-Controlled Mechanism; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in coin-controlled mechanism, and has special reference to the construction of the chute into which the coin is dropped and through which it passes to the operative position.

20 My object is to provide a device of this class whose channel may be kept free for the passage of the coin; and to this end the chute is provided with a movable part arranged to be opened by an actuating device whereby 25 the channel of the chute may be cleared of any material that obstructs it preparatory to the introduction of the coin.

20 The invention will now be described in detail, reference being made to the accompanying drawings, in which is illustrated an embodiment thereof.

35 In the drawings, Figure 1 is a section taken through the casing to which my improved coin-chute is applied, the chute being shown in front elevation. Fig. 2 is a section taken through the casing at right angles to the section in Fig. 1, the parts being viewed from a point at the left of Fig. 1. Fig. 3 is a perspective view in detail of the coin - chute 40 viewed from the rear of Fig. 1 or from a point at the left of Fig. 2, the hinged part of the chute being raised sufficiently high to disclose its inner surface and the plate forming the rear part of the coin-receptacle at the bottom of the chute being removed.

45 The same reference characters indicate the same parts in all the views.

Let the numeral 5 designate a suitable casting to which the main part 6 of the chute is secured by means of screws 7. One of these screws is passed through a slot 6^c, formed in

an angle part 6^a, belonging to an arm 6^d of the chute part 6. The other screw 7 is passed through an opening formed in a flange 6^b, formed on the part 6^d, comprising one of the 55 sides of the coin rest or receptacle at the bottom of the chute. The opposite side of the coin-rest consists of a plate 8, adapted to be secured to the plate 6^d by screws 9 passing through registering apertures 8^k and 6^k, 60 formed in the respective parts.

The movable part 10 is hinged on the part 6 by a pin 12 passing through registering apertures formed in ears, with which the upper portions of the two parts are provided. The 65 hinged part 10 is provided with side flanges 10^a, which engage the part 6 and form a channel for the coin. The latter after passing by gravity through the channel of the chute rests on a lug 6^m on the lower extremity of 70 the part 6. The coin also when in this portion of the rest engages a device 13^a, attached to a dog 13, fulcrumed on the casing by means of a bolt 14. This dog normally locks the operating mechanism (not shown) against 75 movement. The locking position of the dog is shown in full lines in Fig. 1. When the coin is in the position of rest, as aforesaid, the dog 13 is actuated to release the mechanism by pressing downwardly on a rod 15, 80 which, as shown on the drawings, passes through an opening in the top of the casing and a guide-lug 6^s, formed on the lower portion of the part 6. The upper extremity of this rod projects above the casing, while its 85 lower extremity normally occupies a position in the coin-rest just above the coin, the plate 8 being provided with an outward swell or bend 8^a for the purpose. The rod is also surrounded by a coil-spring 16, whose lower extremity rests upon the guide-lug 6^s, while its upper extremity engages a suitable stop on the rod. By pressing downwardly on the rod 90 the coin will be forced against the part 13^a of the dog and the latter moved to the dotted-line position in Fig. 1. The spring 16 being compressed by the downward movement of the plunger-rod returns the latter to its normal position as soon as the pressure on the rod ceases to act.

95 The rod 15 is provided with a projection 17, which normally occupies a position in the slot

of a lug 10^d, with which the upper extremity of the chute part 10 is provided. As shown in the drawings, the projection 17 is provided with a threaded shank which passes through 5 a threaded opening formed in the rod 15, whereby the said projection is adjustable to regulate the movement imparted to the hinged part of the chute. Whenever the plunger-rod is pushed downwardly, as here- 10 tofore explained, the projection 17 engages the hinged part 10 above the hinge-pin 12 and throws the said part outwardly to the dotted-line position in Fig. 2. This outward movement of the said part is sufficient to re- 15 lease an obstruction of any kind which may be introduced at the mouth of the chute, the said mouth being necessarily exposed to receive the coin. Hence preparatory to inserting the coin the rod should be depressed in 20 order to open the part 10 to allow anything that may obstruct the channel of the chute to drop out. The rod is then released and returned by the spring to its normal position. The coin is then inserted and passes through 25 an unobstructed channel of the chute. The coin after it passes through the main portion of the channel drops upon the ledge 10^e at the bottom of the chute part 10 and rolls downwardly into the coin-rest, since the ledge 30 is downwardly inclined in the direction of the rib 6ⁿ.

The chute is adjusted to occupy such a position that the part 10 of the chute will normally remain closed by gravity. The position of the chute with reference to the closing of the part 10 may be regulated by loosening the screws 7, whereby the chute may be turned on the lower screw, while the slot 6^c, in which the upper screw is inserted, will permit the necessary movement for the purpose stated.

On machines equipped with my improved device instructions will be given whereby a person wishing to use the machine will press 45 the operating-rod prior to inserting the coin, for reasons which will be obvious from the foregoing description.

My improved device has been designed with special reference to use in connection with 50 street bicycle-pumps which are now in common use, though it is evident that it may be used with all machines in which it is desired to insert a coin previous to use.

It will be observed that the coin-rest of the 55 chute is located at an angle to the body thereof and closed on both sides when the hinged side of the chute is open. By reason of the location of the coin-rest it becomes practically impossible for foreign substances inserted at the exposed mouth of the chute to find lodgment in the coin-rest. Furthermore, the peculiar location of the coin-rest—that is to say, at an angle to the body of the chute—prevents one coin from falling directly on top 60 of the other. When one coin is allowed to fall directly on top of the other, the upper coin is liable to be forced by the coin-eject-

ing rod to one side of the lowermost coin. In this event the two coins may close the discharge-opening of the chute and render it impossible to eject them by the use of the rod. 70

Having thus described my invention, what I claim is—

1. The combination with a casing, of a coin-chute located therein and provided with a 75 hinged side normally held in the closed position by gravity, the upper extremity of the hinged side projecting above the hinging-point, and a spring-supported rod mounted on the casing and provided with a projection 80 adapted to engage the extremity of the hinged part above the axis of the hinge, whereby the said part is opened as the rod is actuated.

2. The combination with a casing and a dog 85 normally arranged to lock suitable mechanism inclosed by the casing, of a coin-chute having a hinged part normally closed, and a device arranged to thrust the coin against a dog whereby the latter is unlocked, the same device having an adjustable projection 90 arranged to open the hinged portion of the coin-chute as the device is actuated.

3. The combination with a casing, of a coin-chute located therein and having a mouth exposed for the insertion of a coin, a channel 95 through which the coin passes, and a coin-rest at the extremity of the channel, one part of the chute being hinged to the other part which is relatively stationary, and a spring-supported rod mounted on the casing and 100 adapted to enter the coin-rest, the said rod being provided with an adjustable projection adapted to engage and open the hinged part of the chute as the rod is actuated.

4. The combination with a casing, of a coin-chute located therein and provided with a hinged side normally held in the closed position by gravity, a spring-supported rod mounted on the casing, and a projection on the rod arranged to open the hinged part of the chute 110 as the rod is actuated, the said projection having a threaded shank engaging a threaded opening formed in the rod, to permit adjustment, whereby the degree of movement imparted to the hinged part may be regulated 115 at will.

5. The combination with a casing, of a coin-chute located therein and provided with a hinged side normally held in the closed position by gravity, a spring-supported rod mounted on the casing, and a projection adjustably mounted on said rod and arranged to open the hinged part of the chute as the rod is actuated. 120

6. The combination with a casing, of a coin-chute located therein and provided with a hinged side, the body of the chute being adjustably mounted on the casing, and a spring-supported rod having a projection adapted to engage the hinged part of the chute whereby 130 as the rod is depressed, the said hinged part is operated for the purpose set forth.

7. A coin-chute provided with a hinged side, and a coin-rest connected with the lower ex-

tremity of the body of the chute but independent of the hinged side, whereby the coin may be retained in the coin-rest when the hinged side is open.

5 8. A coin-chute provided with a body portion having a hinged side, and a coin-rest connected with the lower extremity of the body of the chute, the coin-rest being independent of the hinged side and closed on both sides 10 whereby the coin may be retained in position to perform its function, when the hinged side of the body of the chute is open.

9. A coin-chute provided with a hinged side, and a coin-rest connected with the lower extremity of the body of the chute and extending therefrom substantially at right angles, the coin-rest being independent of the hinged side whereby the coin may be retained therein when the hinged side is open.

15 10. The combination with a casing, and a spring-supported, coin-ejecting rod mounted thereon, of a coin-chute having a hinged side, said side projecting above the hinging-point, the said upward projection being slotted, and 20 a projection having a threaded shank engag-

ing a threaded opening formed in the coin-ejecting rod, said projection engaging the slotted upward extremity of the hinged side of the chute, the arrangement being such that as the rod is forced downwardly the projection acts on the upper extremity of the hinged side and opens the said side below the hinging-point. 30

11. The combination with a casing, of a coin-chute pivotally mounted on the casing, and provided with a slotted projection, and a fastening device passing through said slot and normally holding the chute in the adjusted position, the arrangement being such that by loosening said fastening device, the chute may 35 be adjusted, one side of the chute being hinged and normally held in the closed position by gravity. 40

In testimony whereof I affix my signature in presence of two witnesses.

WARD DARLEY.
